(57) **CLAIM**

The ornamental design for a folded table in folded configuration, as shown and described.

DESCRIPTION

FIG. 1 is an isometric view of a folded table in folded configuration.

FIG. 2 is a front view of the folded table. As all four elevation views are the same in this symmetrical table, only one such view is shown.

FIG. 3 is a top view of a folding table in the folded state, looking down on the top; and,

FIG. 4 is a bottom view of a folding table in the folded state, looking up from the bottom of the legs to the underside of the table.
